CASTER-TRUCK

Filed Feb. 6, 1940

UNITED STATES PATENT OFFICE

2,314,129

CASTER TRUCK

William E. Daley, Alameda, Calif.

Application February 6, 1940, Serial No. 317,540

3 Claims. (Cl. 280—61)

The invention relates to a caster-truck or dolly such as used for supporting and moving stoves, refrigerators, pianos and other heavy articles, over a floor of a dwelling or salesroom.

An object of the invention is to provide a truck of the character described which will be light, compact, and capable of handling relatively large and heavy articles, and yet will require a minimum lifting or raising of the article to permit the truck to be operatively inserted under the base or leg of the article.

Another object is to provide a truck of the character described which will support the leg or base of the article in such manner that there will be no danger of the article becoming dislodged on the truck, or set thereon to induce a tilting of the truck or mar the surface of the portion of the article in contact with the truck.

A further object is to provide a truck with the above advantages which can be manufactured at low cost.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a plan view of the truck of my invention.

Figure 2 is a side elevation of the truck.

Figure 3 is a vertical sectional view of the truck as taken on the line 3—3 of Figure 1.

Figure 4 is a plan view of a set of the trucks shown operatively supporting an object.

As illustrated in the drawing, the caster-truck of my invention comprises a body 5 which includes what may be conveniently termed an article supporting portion or plate 6 and article abutment portions 7. The plate is preferably of triangular form and has two sides 8 at right angles to each other and with the remaining side 9 at equal angles to adjacent sides.

Extending upwardly from the sides 8 of the plate and preferably formed integrally with the plate are flanges 12 which likewise are disposed at right angles to each other and designed to serve as guards or stops against which the article supported on the plate may abut so as to hold the article against displacement on the plate. It is important that the flanges 12 pre-

sent opposed surfaces or abutments at right angles, as in this manner both of the vertical surfaces of the corner of a square or rectangular article or leg thereof, or of any member having vertical outer surfaces at right angles, such as in practically all modern stoves and refrigerators, will have a firm backing against lateral displacement and there will be no danger of the article or leg thereof slipping off the truck, or shifting upon surfaces of different levels on the truck, so as to tend to tilt the truck, or cause a marring of the surface of the article due to the shifting thereof.

The plate portion 6 of the body is arranged to lie relatively close to the ground and in order that an article may be transferred from the ground to and upon said plate with a minimum raising or lifting of the article, the entire side 9 above the plate is left entirely unobstructed. With this arrangement, as may be readily seen, the article need only be raised to substantially the level of the top surface of the plate to permit the appropriate body portion of the truck to be inserted thereunder. Desirably a reinforcing flange 13 is provided along the open side of the plate, but as is clear from Figures 2 and 3, such flange extends downwardly and below the plate so as to leave the body entirely open and unobstructed at said side. As will be evident, the provision of the various flanges adds considerably to the rigidity of the body permitting of the same being formed of a lighter gauge metal for providing a given strength and sturdiness.

The body is designed to be supported preferably upon three casters 15, 16 and 17, which are positioned in general at the corners of the body. The casters 15 and 16 are carried at the opposite ends of a bar 14 which is fixed to the underside of the body plate and extends along but inwardly of the open side 9 and flange 13. The end portions of the bar are extended from the body to provide arms 18, each having an upwardly extending portion 19 and an outwardly extending portion 21. The casters 15 and 16 are carried by the portions 21 and are provided with pivot pins 22 which fit in bearings 23 in such portions, and the vertical portions 19 are positioned sufficiently inward of the bearings that the caster wheels may revolve completely about the pivot pin. As will be clear from Figure 1, a line intersecting the pivotal axes of the casters lies inwardly of the side 9 of the plate. In this manner an article, even if supported close to the open side 9 of the plate, will have its weight readily distributed to these casters without danger of

the body tilting toward the front or open side of the truck. At the same time, there will be no protuberances at the open side of the truck to interfere with the positioning of the truck close or practically against the article before it has been placed upon the truck. The caster 17 is preferably carried upon a bar 26 which is rigidly secured under and to the plate and extends at right angles to the bar 14 and outwardly from the body at the juncture of the top flanges 12. The portion of the bar 26 which extends from the body is in the form of an arm 27 similar to the arms 18 and has provided in the horizontal portion thereof a bearing 28 for the pivot pin 29 of the caster 17. This arrangement of the various casters insures the effective distribution of the weight of the articles to the body and to casters and consequently the most efficient use and ease of operation of the trucks.

In Figure 4 I have shown a typical use of a set of casters in transporting or moving an article such as a refrigerator 31. It will be noted that a caster is positioned under each corner of the article and so that the flanges each engage the sides of the base or legs of the article. With the article thus supported all of the advantages heretofore pointed out in connection with my device will be had.

I claim:

1. A truck of the character described comprising, a body having a supporting surface of triangular form provided with upwardly extending side walls at two sides and a downwardly extending wall at the other side, said body being open at said latter side, an arm extending from said body at the juncture of said first sides, arms extending laterally in substantially opposed directions from said body adjacent the open side there-

of, and casters carried by each of said arms positioned to support said body in spaced relation to the surface upon which the casters may be resting.

5 2. A truck of the character described comprising, a body including an article supporting plate of triangular form with a pair of adjoining sides at right angles, article abutment flanges extending upwardly from the said sides and coextensive therewith, a reinforcing portion for said plate exclusively below and along said plate at the free side thereof, an arm extending from said body at the adjoining ends of said flanges and comprising upwardly and outwardly extending portions, arms extending in substantially opposed directions from said body adjacent the free side of said plate, and casters carried by each of the outwardly extending portions of the arms.

3. A truck of the character described comprising, a body with a triangular horizontal plate having two sides at right angles to each other, flanges extending upwardly from said sides and having adjoining ends, a flange extending entirely below said plate along the other side thereof, said body being entirely unobstructed above said plate along said last side, a bar extending under and secured to said plate inwardly and parallel to said last side and having portions at its opposite ends lying without said body and extending first upwardly then outwardly therefrom, a bar 30 extending from under said plate at right angles to said first bar and the juncture of said first flanges and portions at the outer end corresponding with the first bar, a caster pivot bearing in each of the outwardly extending portions of said bars, and casters mounted in said bearings.

WILLIAM E. DALEY.
